PLATFORM COVER TURNING MACHINE

Robert H. Lawson, Beverly, Mass., assignor to
United Shoe Machinery Corporation, Flemington, N. J., a corporation of New Jersey

Application December 31, 1946, Serial No. 719,587

17 Claims. (Cl. 12—1)

1

This invention relates to machines for turning the platform covers of platform shoes and is herein disclosed as embodied in a machine of the type illustrated and described in United States Letters Patent No. 2,422,737, granted June 24, 1947, upon my application and also in my co-pending application Serial No. 656,457, filed on March 22, 1946. The illustrated machine like the machines disclosed in my applications just mentioned is provided with a pair of U-shaped turning tools adapted to fit around the respective ends of an inverted shoe and to engage within the unturned platform cover. The turning operation is performed by urging the shoe downwardly first into one of the U-shaped tools and then into the other tool by means of a plunger operating against the shoe bottom.

It is an object of the present invention to provide a power operated platform cover turning machine of the type under consideration. In accordance with a feature of the invention the illustrated machine is provided with a safety device which prevents the starting of the machine unless one or the other of the turning tools is in its operating position. The turning tools are conveniently mounted upon a sector shaped carrier which may be swung toward the right or the left about a pivotal support to bring the selected tool into operating position.

These and other features of the invention are illustrated in the drawings and are hereinafter described and claimed.

Referring to the accompanying drawings,

Fig. 1 is a side elevation partly in section showing the operating instrumentalities of an illustrative machine in their initial positions;

Fig. 2 is a front elevation of the machine showing the parts in their initial positions;

Fig. 3 is a plan view of the machine with the top cover removed;

Fig. 4 is a sectional view in plan of the driving mechanism of the machine;

Fig. 5 is a view in side elevation showing the shoe engaging members at the beginning of the operation;

Fig. 6 is a view similar to Fig. 5 illustrating a later stage of the operation;

Fig. 7 is a side elevation of the clutch control mechanism with the clutch disengaged;

Fig. 8 is a side elevation of the clutch mechanism with the clutch engaged;

Fig. 9 is a view similar to Fig. 8 showing the clutch mechanism being disengaged at the completion of a cycle;

Fig. 10 is a sectional view in elevation taken on the line X—X of Fig. 1;

Fig. 11 is a plan view in section taken on the line XI—XI of Fig. 10;

Fig. 12 is a plan view in section taken on the line XII—XII of Fig. 10;

2

Fig. 13 is a plan view in section taken on the line XIII—XIII of Fig. 10; and

Fig. 14 is a plan view of the turning tools together with the mechanism for adjusting them.

The shoe engaging members of the illustrative machine comprise a heel turning tool 10, a toe turning tool 12, a shoe bottom engaging plunger 14, a tool 16 which serves to push a shoe forwardly during the operation, and a friction tool 18 which operates to assist the plunger 14 in turning a platform cover C of a shoe S over the tool 10. The shoe S, as shown herein, is mounted on a last L and it has a platform, comprising a midsole M and a wedge heel H.

The supporting structure of the machine comprises a hollow sheet metal column 20 (Fig. 2) adapted to rest upon the floor and having a rectangular cross-section, and a head 22 mounted upon the column 20 and consisting of a generally rectangular box-like housing member having a bottom wall or base plate 23. Formed in the right, left, and rear sides of the head 22 are openings which are closed by removable covers 24, 26 and 28 (Fig. 4), respectively. The head 22 (Fig. 2) has also, in its front wall, an opening

25 which is not closed and through which pass several of the moving parts of the machine. The top of the head 22 is closed by a cover 30 hinged by pintles 31 (Fig. 3) to the rear cover 28.

The plunger 14 (Fig. 2) is a U-shaped plate having its under surface toothed for engagement with the work. This plunger is carried upon a lever 32 fulcrumed for limited swinging movement upon a pin 34 (Fig. 1) which extends between a pair of ears 36 upon the forward end of a lever 38. A spring 40 housed in a bore formed in the lever 38 and acting, through a plunger 42, against a tail 44 extending upwardly from the lever 32 normally maintains the lever 32 in a stop position determined by the engagement of the head of a stop screw 46 with the tail 44. The lever 32 is free to yield, against the compression of the spring 40, as far as permitted by a stop screw 48 threaded for adjustment through the tail 44 and engageable with the end surface of the lever 38.

45 The plunger 14 is pivotally mounted upon a pin 50 secured in the lower portion of the lever 32. A spring-pressed plunger 52 housed in a lug in the lever 32 has a flat under-surface which bears against a flat upper surface on the plunger 14 to maintain the plunger yieldingly in a predetermined angular position with respect to the lever 32.

The lever 38 extends from and is integral with 55 a hub 54 which is freely rotatable upon a pin 56 secured in and extending across the head 22. Also integral with the hub 54, and extending forwardly therefrom, is an arm 58 having formed upon its forward edge portion a cam 60. The lever 38 and the arm 58 normally occupy a posi-

tion wherein the plunger 14 is up out of contact with the work, and the lever and the arm are moved downwardly by a mechanism which will later be described. Each downward movement of the lever and the arm causes the work-engaging members to perform their respective operations.

The tool 16 (Figs. 1, 2, 5, 6 and 11) is an arcuate member (Fig. 11) engageable with the toe or heel end of the shoe to push the shoe forward far enough to enable the midsole at the end of the shoe to clear the edge of the turning tool 10. It has a rearwardly extending shank 61 which is clamped to a bracket 62 by a screw 64 extending through a slot formed heightwise in the shank 61 to provide for heightwise adjustment of the member 16. The bracket 62 is carried upon a block-shaped end portion 65 (Figs. 5, 6, 10, 11, 12, and 13) of a bar 66 and is secured upon said portion 65 by a pair of clamping screws 68 passing through slots 70 to provide for forward and rearward adjustment of the member 16. The bar 66, at its block portion 65, is pivotally connected by a pin 72 (Fig. 6) to the upper ends of a pair of parallel swinging arms or levers 74, the lower ends of which are integrally connected by a hub 76 which is rotatable upon a fulcrum pin 78 secured in and extending across the head 22. The bar 66 at its rear end is pivotally connected by a pin 80 (Figs. 5 and 6) to the upper end of a link 82. The lower end of the link 82 is pivotally connected by a pin 84 to an arm 86 substantially parallel to the bar 66, the arm 86 being mounted for free swinging movement upon a pin 88 secured in and extending across the head 22. The link 82 and the arm 86 support the rear end of the bar 66 against undesired lateral movement while leaving it free to move longitudinally and heightwise. A compression spring 90 bearing against a fixed portion of the head 22 yieldingly holds the lower end of the link 82 in an upper limiting position which is adjustably determined by a stop screw 92 threaded into a fixed portion of the head 22 and having its head engageable with a pair of ears 94 formed on the link 82.

Freely rotatable upon a stud 96 (Fig. 5) secured in the right-hand lever 74 is a roll 98 engageable with the operative face of the cam 60, the roll 98 and the cam 60 thus constituting a pair of cooperating cam elements. A tension spring 100 anchored at one end to the lever 38 and at its other end to the bar 66 urges the bar rearwardly to maintain the roll 98 in contact with the cam 60.

The friction tool 18, which is best shown in Figs. 2, 5, 6, 11, 12, and 13, consists of a plate having a concave work-engaging face upon which are formed upwardly directed teeth 102 which engage the platform cover C and urge it upwardly to facilitate its being turned over the U-shaped turning tool. The upper portion of the friction tool 18 is slotted at 103 (Fig. 12) to accommodate the shank 61 of the pushing tool 16, said shank serving to guide the tool 18 in its heightwise movement. The lower portion of the tool 18 (Fig. 6) has formed upon it a hub 104 by which the tool is pivotally mounted upon pin 106 carried by a lever 108. The hub 104 is slotted (Fig. 13) to accommodate the upper end of a tension spring 110 which is secured to the pin 106. The lower end of the spring 110 is anchored to a pin 112 (Fig. 6) secured in a stationary portion of the machine frame. The lever 108, which is in the general shape of the letter H (Fig. 13), consists of a pair of parallel lever arms connected by a

cross bar 114. The two arms of the lever 108 embrace the downwardly extending block portion 65 of the bar 66 and they are pivotally mounted upon the portion 65 by means of a fulcrum pin 116 (see also Fig. 6). Formed upon a rearward extension of the right-hand arm of the lever 108 is an abutment 118. Pivotally secured by a pin 120 (Fig. 5) upon the lever 38 is a depending dog 122, the lower end of which is engageable with the abutment 118 to swing the lever 108 in a clockwise direction as the lever 38 descends, thereby raising the tool 18. Secured in the block portion 65 is a pin 124 against which the dog 122 is yieldingly held by a tension spring 126 secured at one end to a lug extending from the dog and at its other end to the lever 38. The effect of the spring 126 is to urge the dog 122 in a clockwise direction to yieldably maintain its forward face against the pin 124. Formed upon the forward face of the dog 122 is a cam rise 128 which, as the dog descends, engages the pin 124 to swing the dog in a counter-clockwise direction and thereby disengage it from the abutment 118 to release the tool 18, thereby enabling the spring 110 to retract the tool 18. The pin 124 may, for the purposes of adjustment, be provided with an eccentric disk portion like the disc 118 shown in said application Serial No. 656,457. In order to hold the tool 18 against the platform cover, there is provided a roll 130 (Figs. 5, 6, and 12) which engages a ridge 132 (Fig. 12) formed upon the rear face of the tool 18. A torsion spring may, if desired, be employed to hold the tool 18 back against the roll 130. The roll 130 is freely rotatable upon a stud 134 secured in a bracket 136 (Figs. 5, 10, and 12) which in turn is clamped upon the block portion 65 by a clamping screw 138. A horizontally extending slot in the bracket 136 accommodates the screw 138 for forward and rearward adjustment of the bracket 136 as shown in Fig. 12. The ridge 132 extends from the top of the tool 18 down to about the level of the lowest tooth 102 on the operating face. When the tool 18 has risen to a point at which the lowest tooth is in engagement with the platform cover the ridge 132 will ride off the roll 130 and release the operating pressure of the tool 18 against the work. The bracket 136 may be adjusted forward and rearwardly on the block portion 65 to vary the position of the roll 130 for different thicknesses of the platform covers on various types of shoes, and also for varying the pressure which the tool exerts against the work. Downward movement of the tool 18 is limited by a stop 140.

The turning tools 10 and 12 are adapted for operation at the heel and toe ends of the shoe, respectively. These members are stationary while the operation is being performed, but they are mounted for movement to enable either to be moved into its operating position while the other is moved out of operating position. To this end, these tools are mounted upon the top of a sector-shaped bracket 142 (Figs. 1 and 2) which, at its lower end, is mounted for transverse swinging movement upon a pivot pin 144. This pin 144 is rotatable in a bearing formed in the lower end of a bracket 146, the upper end of which is secured by clamping screws 148 to the forward face of the head 22. A block 150 carried by an upstanding stud 152, which is secured in the bracket 146, engages an arcuate guideway 154 (Fig. 2) formed in a flange 156 depending from the under surface of the peripheral rim of the sector-shaped bracket 142 to guide the bracket in its swinging movement. Extending across the slot 154 is a pin

158 (Figs. 2, 5, 6 and 7) having eccentric bearing portions 160 which are rotatable in the flange 156 to provide for adjustment. This pin 158 engages the left-hand end face of the block 150 to stop the bracket 142 in proper position to bring the heel turning tool 10 into register with the other work-engaging members of the machine. A similar stop pin 162 (Fig. 2) engageable with the right-hand face of the block 150 is provided to stop the bracket 142 with the toe turning tool 12 in improper operating position.

The tool 10 (Figs. 1, 2, 5, 6 and 14) is a U-shaped member comprising a curved rear portion from which a pair of substantially parallel arms extend forward, this shape being such as to enable the member to engage the heel end of a shoe. It is composed of spring steel and is supported by a pair of integral downwardly extending arms 164 at each of its side portions. The lower ends of each pair of arms 164 are integrally connected by a base portion 166. The right-hand base portion 166 (Fig. 14) is clamped by screws 168 to an upstanding lug 170 formed upon a slide 172. The left-hand base portion 166 is clamped by screws 174 to an upstanding lug 176 formed on a slide 178. The slides 172 and 178 are slidable upon a flat face formed on the periphery of the sector-shaped bracket 142. Four guide members, indicated by the reference characters 180, 182, 184, and 186, are secured upon the flat face of the bracket 142 in such a way as to form two guideways in which the respective slides are movable. As shown in Fig. 14, the guideways thus provided for the slides 172 and 178 are angularly disposed to each other by approximately 120° in the form of the letter V. The inherent resilience of the spring steel, of which the tool 10 and its integral supporting members are formed, normally maintains the tool in open position enabling it to fit the heel of a large-sized shoe. To adapt the tool 10 to fit a smaller sized shoe the slides 172 and 178 may be moved closer together to bring the operating portion of the tool 10 into the dash line position indicated in Fig. 14. This adjustment is effected by means of a hand lever 188 pivotally mounted upon a fulcrum pin 190 secured in the periphery of the bracket 142. Extending from the lever 188 is an integral arm 192 having a rounded end which engages a rounded notch in the slide 172. The swinging movement of the lever about its fulcrum serves to move the slide 172 along its guideway. Equal and opposite movement of the slide 178 is simultaneously effected by means of a bell crank 194 pivotally mounted upon a fulcrum pin 196 secured in the bracket 142 and having a pair of arms with rounded ends which engage rounded notches formed, respectively, in the lever 188 and the slide 178. While, as has already been stated, the resilience of the tool itself tends to maintain it in a position of adjustment for large-sized shoes, the tool can be held in the various positions of adjustment for smaller sizes by means of a ratchet 198 secured by studs 199 upon the face of the bracket 142 and engageable by a multi-toothed pawl 200 formed upon a slide 202. A pair of studs 204 threaded into the lever 188 and engaging longitudinal slots formed in the slide 202 guide the slide for movement to engage the pawl 200 with or disengage it from the ratchet 198. A hand grip 206 having a bell crank extension by which it is fulcrumed upon one of the studs 204 is pivotally connected by a pin 208 to a lug extending from the slide 202. A spring 209 normally holds the handgrip 206 away from the lever 188. The op-

erator, by squeezing the hand grip 206 as he grasps the hand lever 188, can disengage the pawl from the ratchet to enable him to make the desired adjustment.

The toe turning tool 12 is in a general way similar to the heel turning tool 10, but its forwardly extending arms diverge to enable it to conform to the toe end of a shoe. It has, on each side, a depending integral portion 210 generally similar to the corresponding portions of the tool 10. The left-hand depending portion 210 of the tool 12 is secured to an upstanding lug 212 formed on a slide 214. The right-hand depending portion 210 is secured to an upstanding lug 216 formed on a slide 218. The slides 214 and 218 are slidable in an arcuate guideway formed by four guide members, 220, 222, 224, and 226 secured to a flat face of the bracket 142. Adjustment of the toe turning tool 12 simultaneously with that of the U-turning tool 10 is effected by means of a three-armed lever 228 fulcrumed upon a pin 230 secured in the bracket 142 and having an arm 232 with a rounded end engaging a notch formed in an extension 234 of the adjusting lever 188. Another arm 236 extending from the lever 228 has a rounded end engaging a notch in the slide 214 to move the slide in its guideway. The third arm of the lever 228 has a rounded end 238 which engages a rounded notch formed in one arm of a bell crank lever 240 fulcrumed upon a pin 242 secured in the bracket 142. A second arm of the bell crank lever 240 has a rounded end 243 which engages a notch in the slide 218. The purpose of the angularly disposed guideways for the slides of the tool 10 and the arcuate guideway for the slides of the tool 12 is to insure that the positions of the most rearward points, P and P', as shown on Fig. 14, of the work-engaging portions of these tools will not vary forwardly or rearwardly when the tools are adjusted for different sized shoes. The angularly disposed guideways for the tool 10 maintain the forwardly extending arms of that U-shaped tool substantially parallel for all size adjustments, and the arcuate guideway for the tool 12 insures an increase in the divergence of the forwardly extending arms of that U-shaped tool as the tool is adjusted for larger sizes.

The machine is driven by a motor 244 (see Fig. 1) mounted upon a bracket 246 which is secured upon the rear wall of the column 20. As shown in Fig. 1, the rear wall of the sheet metal column has an opening which extends vertically and at the edges of which the material which forms the column has inwardly extending flanges 245. Secured upon the shaft of the motor 244 is a pulley 248 which drives a belt 250. The upper portion of the belt 250 is looped about a pulley 252 which rotates freely upon ball bearings and which is thus continuously driven. The inner raceway of the ball bearings (Fig. 4) is secured upon the reduced end of a stationary shaft 254 and it holds the pulley 252 against longitudinal movement. The shaft 254 is supported at its forward end by a boss 256 which extends upwardly from the base 23 and at its mid portion in a boss 258 which also extends upwardly from the base 23. The reduced rear portion of the shaft 254 extends through an opening in the rear cover 28 and has threaded upon it a nut 260 which, when tightened, serves to hold the above-mentioned inner raceway against a boss extending inwardly from the cover 28, thereby holding the shaft 254 against axial and rotary movement. A set screw secures the forward end of the shaft

254 in the boss 256 to assist the nut 260 in holding the shaft stationary. Freely rotatable upon the shaft 254 is a clutch member 262 having a hub 264 and a facing 266 of friction material which is engageable with the adjacent face of the pulley 252. The hub 264 is slidable axially upon the shaft 254 to enable the clutch to be engaged and disengaged. Mechanism for operating the clutch will later be described.

Secured upon the hub 264 is a pinion 268 (see Figs. 4 and 5) which drives a gear 270 secured upon a hub 272. This hub 272 is freely rotatable upon a stationary countershaft 274 secured at its forward end in a boss 276 extending upwardly from the base 23 and at its rearward end by a boss 278 also extending upwardly from the base plate 23. A pinion 280 secured upon the hub 272 drives a gear 282 secured upon a hub 284 which is freely rotatable upon the stationary shaft 254 and which is held against axial movement of said shaft by the engagement of its ends with finished surfaces on the bosses 256 and 258. Secured upon the hub 284 is a pinion 286 which meshes with a vertical rack 288 formed upon a rack bar 290. This rack bar is guided for heightwise movement in a guideway formed in the boss 256. Pivotally connected to the upper end of the rack bar 290 is the lower end of a link 292, the upper end of this link being pivotally connected to the lever 38.

When the clutch is disengaged the lever 38 is normally held in its uppermost position by a pair of parallel tension springs 294 (Figs. 1 and 2) the upper ends of which are anchored in the base 23 and the lower ends of which are secured to a cross bar 296 secured to the lower end of a vertical rod 298. The upper end of the rod 298 is secured in the rack bar 290, the rod 298 thus forming a downward extension of the rack bar. The lower end of the rack bar 290 extends through an opening in the base 23 and it has mounted thereon a padded washer 300 which engages the under-surface of the base 23 to limit the upward movement of the lever 38 under the influence of the springs 294.

The clutch above described is engaged by the depression of a starting handle 302 which extends forwardly from a hub 304 (Figs. 2 and 3) which is freely rotatable upon a shaft 306. This shaft 306 is freely rotatable in a bearing formed in a boss 308 (Fig. 4) on a side wall of the head 22 and in another bearing formed in the boss 258. The hub 304 extends to the left of the head 22 through an opening formed in the left-hand cover plate 26. Extending upwardly from the hub 304 are a pair of arms 310 and 312 (see also Fig. 7). Secured upon the outer end of the shaft 306 is a hub 314 from which an arm 316 extends upwardly and inwardly between the arms 310 and 312. A spring 318 housed in the arm 312 and backed by a screw 320 bears against the arm 316 to hold the arm 310 normally against the arm 316. Depression of the starting handle 302 operates yieldingly, through the spring 318, to rotate the arm 316 in a clockwise direction as viewed in Figs. 7, 8, and 9 and thus to rotate the shaft 306 also in a clockwise direction. Such depression of the starting handle 302 is limited by a stop screw 321 threaded for adjustment through a lug 323 in the cover 26 and engageable by the arm 310. Secured upon the shaft 306 is a hub 322 (Fig. 3) from which extends rearwardly an abutment lug 324 (Figs. 8 and 9). Engageable with the lug 324 is the lower end of an arm 326 which extends downwardly from

5 a hub 328. A pivot pin 330 extending through the hub 328 connects the upper end of the arm 326 with a lever 332 having at its lower end a hub 333 which is mounted for rotary movement upon a fulcrum pin 334 secured at one end in a boss on the head 22 and at its other end in the boss 278. The lever 332 has a portion 336 which extends upwardly on one side of the hub 264. An arm 337 extends upwardly from the hub 333 on the opposite side of the hub 264, and a pair of co-axial diametrically opposed pins 338 secured respectively in the portion 336 and the arm 337 extend into a circumferential groove 340 formed in the hub 264 and serve, upon movement of the lever 332, to shift the movable clutch member 262 into and out of engagement with the pulley 252. It is evident that with the construction so far described, depression of the starting handle 302 will cause the abutment lug 324 to push the arm 326 upwardly and thereby swing the lever 332 in a counter-clockwise direction as viewed in Figs. 8 and 9 to engage the clutch and thereby start the drive of the machine.

20 To prevent the clutch from being engaged, except when either of the turning tools 10 or 12 is in its operative position, there is provided a safety lever 342 which extends forwardly from a hub 344 (Fig. 3) through openings in the front wall of the head 22 and in the bracket 146. The hub 344 is secured by a set screw upon the shaft 306. Extending upwardly from the hubs 333 and 322 are arms 345 and 346. A tension spring 348, secured at its ends to the arms 345 and 346, normally holds the clutch disengaged, and it also holds the safety lever 342 up in a stop position determined by the engagement of a stop screw 350 (Figs. 8 and 9) threaded downwardly through a lug 352 formed on the hub 344, the bottom of the screw 350 being engageable with the head of a screw threaded into the base 23.

30 Accidental engagement of the clutch is prevented by an arcuate surface 354 (Figs. 1, 3, 7 and 8) formed on the periphery of the sector 142 and concentric with the pin 144, this arcuate surface extending under the forward end of the safety lever 342 to prevent depression thereof. The sector 142, however, has two notches formed in its periphery, one or the other of which is in register with the safety lever 342 when the corresponding turning tool 10 or 12 is in its operating position. One of these notches is indicated on Figs. 1, 5 and 6 by the reference numeral 356. As long as the surface 354 is under the end of the safety lever 342 the shaft 306 cannot be turned and the clutch, therefore, cannot be engaged.

40 Disengagement of the clutch at the end of an operation is effected automatically by a block 358 (Figs. 8 and 9) secured upon a face of the gear 282 and engageable with an arm 360 extending from the hub 328. Rotation of the gear 282 causes the block 358 to descend and, upon engaging the arm 360, to rotate the hub 328 and, therefore, the arm 326 in a clockwise direction to disengage the arm 326 from the abutment lug 324. The spring 348 thereupon swings the lever 332 in a clockwise direction and disengages the clutch and, as soon as the operator releases the starting handle 302, this spring serves also to raise the safety lever 342 into its normal position. A spring-pressed plunger 362 housed in a hollow boss on the lever 332 bears against the arm 326 to restore the arm to its position of engagement with the abutment lug 324 as soon as the starting handle 342 has been raised into its normal position. A spring 364 housed in a block 366, mount-

ed for heightwise adjustment on the boss 258, cushions the downward movement of the arm 360 and absorbs the momentum of the gear 282 when the arm 360 is struck by the block 358. Extending rearwardly from the hub 328 is an arm 368 which normally engages a flat surface on the lever 332 to limit the counter-clockwise movement of the arm 326 under the influence of the spring-pressed plunger 362, normally holding it in position to engage the abutment lug 324.

In the operation of the machine, one end of the shoe is mounted upon one of the U-shaped turning tools, the heel end, for example, upon the tool 10 while the bracket 142 occupies the left-hand limit of its range of movement to maintain the tool 10 in its out-of-the-way position. A convenient way of mounting the heel end of the shoe upon the tool is described in Letters Patent No. 2,422,737 above mentioned. The bracket 142 is then swung to the right-hand limit of its range of movement to bring the tool 10 into operating position and the starting handle 302 is depressed to start the power drive of the machine.

The lever 38 is thus lowered, against the force of the springs 294, by power exerted through the clutch and gearing above described. As the lever 38 descends, it brings the plunger 14 into contact with the shoe bottom and causes the plunger to push the heel end of the shoe down inside the tool 10, thereby obliging the cover C to turn right side out over the tool. The resistance encountered by the plunger 14 upon engaging the shoe bottom causes the plunger to swing forward about the pin 34, thereby urging the shoe forward to enable the extension of the platform of the shoe to clear the tool and pass down within the tool. Such forward movement of the shoe is further insured by the tool 16, which moves forward under the force exerted by the descending cam 60 against the roll 98.

The tool 16 not only pushes the shoe forward, but it bears down upon the cover C to press the cover frictionally against the tool 10, thereby exerting a snubbing effect to tension the cover and remove wrinkles. The tool 16 is yieldingly held down in a stop position by the spring 90, which urges the rear end of the bar 66 up as far as permitted by the stop 92. The normal heightwise position of the tool 16 may be adjusted for various thicknesses of the covers to be turned, and also for the various degrees of frictional pressure desired, by turning the threaded stop 92 to vary the height of its head. The tool 16 is free to yield up, compressing the spring 90 in response to the thickness of the cover.

The friction tool 18 is often desirable for work upon leather platform covers which are relatively stiff and resistant to the turning operation. It is raised by the descending tip of the dog 122 which engages the abutment 118 and swings the lever 108 in a clockwise direction as viewed in Fig. 5. The degree of pressure of the tool 18 against the work is determined by adjusting the bracket 136 forwardly or rearwardly, and, if the nature of the work does not require its use, the tool 18 may readily be adjusted rearwardly to an inoperative position or even removed from the machine. The tensioning effect of the tool 16 is usually desirable when working upon leather covers as well as upon covers of more flexible material, but in the case of unusually stiff work it may be lightened or eliminated by downward adjustment of the stop 92.

The operator has continuous control over the power driven instrumentalities during the

course of the operation. He can lighten his pressure on the starting handle 302 and permit the clutch to slip, or even to disengage when there is any danger of the strain upon the work becoming excessive and, while the moving parts are thus rendered stationary, or returned by the spring 294 to their initial positions, he may manipulate the work as conditions may require before making a fresh start. After the plunger 14, the pushing tool 16 and the friction tool 18 have performed their respective operations in the manner already described, and as the rack 290 reaches the lower limit of its range of movement, the clutch member 262 is automatically disengaged and the springs 294 restore the power driven members to their initial positions. The operator then removes the shoe from the heel turning tool, and mounts the toe end of the shoe upon the toe turning tool 12; he then swings the bracket 142 to the left-hand limit of its range of movement to bring the tool 12 into operative position and depresses the starting handle 302, whereupon the power driven members again perform their respective operations in the manner already described.

Having described my invention, what I claim as new and desire to secure by Letters Patent of the United States is:

1. A platform cover turning machine comprising a pair of cooperating members constructed and arranged to turn the platform cover of a shoe upon the operative movement of one member relative to the other member while said other member is stationary, a support constructed and arranged for movement of said stationary member into and out of operating position with respect to the operatively movable member, means for causing the operatively movable member to perform its operative movement, and a safety device normally preventing such operative movement, said safety device being constructed and arranged to permit such operative movement when the stationary member is in its operating position.

2. A platform cover turning machine comprising a pair of tools adapted for operation upon the platform cover of a shoe at the heel and toe ends respectively of the shoe, means cooperable with either of said tools to turn the platform cover, a common support for said tools movable to bring either tool into operating position with respect to said cooperable turning means while bringing the other tool into an out-of-the-way position, means for causing said turning means to cooperate with either of said tools to turn the platform cover, and means for preventing the operation of said causing means when both tools are out of operating position.

3. A platform cover turning machine comprising a pair of cover-turning tools adapted to operate at the heel and toe ends respectively of a shoe, a third tool movable in a predetermined path for cooperating with said cover-turning tools to turn the cover at the heel and toe ends of the shoe, a carrier for said pair of cover-turning tools mounted for movement to enable the tools of said pair to be brought alternatively into operative position relatively to the third-mentioned tool, means for moving the third-mentioned tool to cause it to perform a cover-turning operation, and means for rendering said moving means inoperative whenever said carrier occupies a position such that neither tool of said pair is in its operative position.

4. A platform cover turning machine comprising

ing a pair of cover-turning tools adapted to operate at the heel and toe ends respectively of a shoe, a third tool movable in a predetermined path for cooperating with said cover-turning tools to turn the cover at the heel and toe ends of the shoe, a carrier for said pair of cover-turning tools mounted for movement to enable the tools of said pair to be brought alternatively into operative position relatively to the third-mentioned tool, a power driven means for moving the third-mentioned tool to cause it to perform a cover-turning operation, a clutch in said power-driven means constructed and arranged to be engaged by the operator and to disengage automatically at the end of a single operation, and means for preventing the engagement of said clutch when the carrier occupies a position such that neither tool is in its operative position.

5. A machine for turning the platform covers of platform shoes comprising a pair of cover-turning tools adapted to operate at the heel and toe ends respectively of a shoe, a tool movable in a predetermined path for cooperating with said cover-turning tools to turn the cover at the heel and toe ends of the shoe, a carrier for said pair of cover-turning tools, said carrier being mounted for swinging movement to enable the tools of said pair to be brought alternatively into operative position relatively to the tool which is movable in a predetermined path.

6. A platform cover turning machine comprising a pair of cooperating members constructed and arranged to turn the platform cover of a shoe upon the movement of one member relative to the other, means for moving one of said members operatively with respect to the other, a releasable connection in said moving means, and means for releasing said connection to terminate such relative movement.

7. A platform cover turning machine comprising a turning tool engageable with the platform cover of a shoe, a plunger engageable with the shoe, resilient means normally holding said plunger in an initial position, power driven means for moving said plunger in opposition to said resilient means to cause the plunger to move the shoe operatively with respect to said turning tool, a releasable connection in said moving means, and means for releasing said connection to terminate the operative movement of the plunger and to enable the resilient means to return the plunger to its initial position.

8. A platform cover turning machine comprising a tool constructed and arranged to engage within the platform cover at an end of a shoe, a plunger engageable with the shoe bottom to move the shoe relatively to said tool to cause the platform cover to be turned, resilient means for normally holding the plunger away from the shoe bottom, operating means for causing said plunger to perform an operative movement, and means for releasing said operating means from said plunger to permit the resilient means to restore the plunger to normal position at the end of its operative movement.

9. A platform cover turning machine comprising a turning tool engageable with the platform cover of a shoe, a plunger engageable with the shoe, a rack, a driving connection from said rack to said plunger, resilient means normally holding said plunger in an initial position, driving means geared to said rack for causing the plunger to move the shoe operatively with respect to said turning tool and in opposition to said resilient means, a clutch in said driving means, and means

for disengaging said clutch to terminate the operative movement of the plunger and to enable the resilient means to return the plunger to its initial position.

5. 10. A platform cover turning machine comprising a tool constructed and arranged to engage within the platform cover at an end of a shoe, a plunger engageable with the shoe bottom to move the shoe relatively to said tool to cause the

10 platform cover to be turned, a member for pushing the shoe longitudinally to cause the extension of the platform of the shoe to clear the tool, a pair of cooperating cam elements through which said pushing member is operated, a rigid member carrying one of said cam elements, means for mounting said plunger on said rigid member, and means for moving said rigid member to cause the plunger and the cam element on the rigid member to move in unison.

20 11. A platform cover turning machine comprising a tool constructed and arranged to engage within the platform cover of a shoe at an end of the shoe, a plunger engageable with the shoe bottom to move the shoe relatively to said tool to

25 cause the platform cover to be turned, a tool for moving the shoe longitudinally to cause the extension of the platform of the shoe to clear the first-mentioned tool, a tool frictionally engageable with the platform cover to assist the plunger in

30 turning the platform cover over the first-mentioned tool, power driven means for operating the plunger, the tool for moving the shoe longitudinally, and the friction tool, a clutch in the power driven means, and means for automatically

35 releasing said clutch to stop the drive at the completion of an operation.

12. A platform cover turning machine comprising a turning tool adapted to engage within the platform cover at an end of a shoe, means for

40 effecting relative movement heightwise of the shoe between said shoe and said tool to turn the cover, a tool for pushing the shoe longitudinally to cause the extension of the platform cover to clear the turning tool, a longitudinally extending bar upon

45 the forward end of which said pushing tool is mounted, means for moving the bar longitudinally to cause the pushing tool to push the shoe, a swinging arm for supporting the bar as the bar moves longitudinally, a pivotal connection be-

50 tween the arm and the bar at the intermediate portion of the bar, and resilient means acting on the bar rearwardly of said pivotal connection to cause the pushing tool to press the platform cover against the turning tool to frictionally retard the 55 cover as it is being turned.

13. A platform cover turning machine comprising a turning tool engageable within the platform cover at an end of the shoe, a plunger engageable with the shoe bottom, means for moving the

60 plunger to cause the shoe to be moved heightwise relatively to the turning tool to turn the cover over the tool, a tool for pushing the shoe longitudinally to cause the extension of the platform cover to clear the turning tool, a longitudinally

65 extending bar upon the forward end of which said pushing tool is mounted, means for moving said bar longitudinally to cause the pushing tool to push the shoe, a swinging arm for supporting the bar as the bar moves longitudinally, a pivotal connection between the arm and the bar at the intermediate portion of the bar, resilient means acting heightwise on the bar rearwardly

70 of said pivotal connection to cause the pushing tool to press the platform cover against the turning tool to frictionally retard the cover as it is 75

being turned, and an adjustable stop for limiting the range of action of said resilient means.

14. In a platform cover turning machine a resilient turning tool having a pair of arms joined by a curved portion, said arms and said curved portion being generally in the shape of the letter U to enable the tool to engage within the platform cover at one end of a shoe, a support for each of said arms, and means for securing said supports in various positions of separation from each other to vary the shape of said turning tool.

15. In a platform cover turning machine, a resilient turning tool having a pair of arms joined by a curved portion from which the arms extend forward, said arms and said curved portion being generally in the shape of the letter U to enable the tool to engage within the platform cover of a shoe at one end of the shoe, a support for each of said arms, a guideway along which each of said supports is movable, said guideways being angularly disposed to each other to provide a rearward component of movement to the supports as the supports are moved away from each other, which rearward component compensates for the tendency of the curved rear portion of the U-shaped tool to move forward as the arms of the U move away from each other, and means for securing said supports in various positions of separation from each other to vary the shape of the resilient U-shaped turning tool.

16. In a platform cover turning machine, a resilient turning tool having a pair of arms joined by a curved portion from which the arms extend forward, said arms and said curved portion being

generally in the shape of the letter U to enable the tool to engage within the platform cover of a shoe at one end of the shoe, a support for each of said arms, a single arcuate guideway along which both supports are movable to vary the distance between them, said guideway being arranged to provide a rearward component of movement to the supports as the distance between them is increased, thereby compensating for the tendency of the curved rear portion of the U-shaped tool to move forward as the arms of the U move away from each other, and means for securing said supports in various positions of separation from each other to vary the shape of the U-shaped turning tool.

17. In a platform cover turning machine, a pair of turning tools each having a pair of arms joined by a curved portion, the arms and the curved portion of each tool being generally in the shape of the letter U, one of said tools being adapted to engage within the platform cover at the heel end of a shoe and the other being adapted to engage within the platform cover at the toe end of the shoe, a support for each of the arms of the heel end turning tool, a support for each of the arms of the toe end turning tool, and a common means for moving all four supports to adjust the degree of separation of the two heel end turning tool supports and at the same time to adjust the degree of separation of the two toe end turning tool supports, said common means serving to adjust the shapes of the turning tools simultaneously.

ROBERT H. LAWSON.
